SPOOL

Walter J. Pasinski, Howell, Mich., assignor to
 Burroughs Adding Machine Company, Detroit,
 Mich., a corporation of Michigan

Original application June 10, 1937, Serial No.
 147,430, now Patent No. 2,264,855, dated Decem-
 ber 2, 1941. Divided and this application Janu-
 ary 4, 1941, Serial No. 373,183

3 Claims. (Cl. 242—74)

This invention relates to cash registers, and more particularly to an improved paper equipment or mechanism for supplying, feeding, storing and controlling a record strip of paper.

The paper equipment is of the type in which the paper is moved from a visible to a printing position and returned to visible position during each machine operation, as disclosed in Patent No. 2,264,855, issued to me December 2, 1941, on my copending application Serial No. 147,430, filed June 10, 1937, of which the present application is a division. The machine has a paper support or table located at some distance from the printing mechanism. A paper strip passes from a supply roll past the printing mechanism and over the paper table to a storage roll. Normally, the last printed entry is in visible position on the table, or through a sight opening. During each machine operation, the paper strip is moved so as to bring it to proper position relative to the printing line of the printing mechanism to enable the next entry to be properly spaced from the last. A line-spacing operation occurs automatically and, after printing occurs, the strip is returned to a visible position so that the currently printed entry is visible.

An object of the invention is to provide a very easy and efficient means for attaching the end of a paper strip to the storage roll, which means also acts automatically to align the paper to insure that the paper will wind evenly and straight upon the storage spool and that it will slide properly on the parts over which it is moved when it is shifted from visible to printing position and returned.

Other objects of the invention will become apparent hereinafter by reference to the annexed specification and drawing.

In the drawing:

Fig. 1 is an enlarged view of the essential elements of the paper mechanism in printing position;

Fig. 2 is a detail perspective view of the paper roll supporting devices with certain parts cut away.

The paper strip P passes from a rotatable paper-supply spool 10 (Fig. 1) under the stationary guiding shaft 11, past the printing line of the printing mechanism, about a stationary guide shaft 14, over the table 15, and over a stationary guide shaft 16 to a rotatable, paper-storage spool 18. The paper strip is moved from a visible to a printing position and returned by bodily moving the supply and storage spools and by arranging them so that, as one spool moves

toward one end of the table, the other spool moves away from the opposite end so that the paper strip is slid over the stationary guides and the stationary table from a visible to a printing position and then returned.

The paper spools are carried by a pair of bell crank levers 21 and 22 (Fig. 2) pivoted on a shaft 23 of the frame of the paper section. The supply spool 10 is rotatably mounted on a shaft 19 carried by the forward arms of said bell crank levers and the storage spool 18 is rotatably mounted on a shaft 2 carried by the upwardly extending arms of said bell crank levers.

The supply and storage spools are moved bodily by means of an arm 26 pivoted at 27 to the machine frame and provided with a cam slot 28 engaging a stud 29 on the lever 30 fixed to a shaft 31. The arm 26 has a cam slot 25 cooperating with a roller 19^a on the end of the shaft 19 that is supported by the two bell cranks 21 and 22. When the lever 30 is rocked forward, as for example by depression of the amount keys, the arm 26 is rocked clockwise, whereupon the cam 25, acting on the roller 19^a, rocks the bell cranks 21 and 22 counterclockwise and thus moves the storage spool 18 toward one end of the paper table 15 while the supply spool moves away from the printing mechanism and the opposite end of said paper table. This slides the paper strip to a position such that the entry being printed will be just below the preceding entry. The parts are timed so that, after the paper strip has been moved to printing position and while it is stationary, the printing mechanism operates to print the current entry. When the parts are released, as by release of the amount keys, they are returned to normal by means including the springs 23 and 33.

Automatic line spacing

When the paper strip is returned from visible position, it must be line spaced and provision is made for automatically accomplishing this as follows:

Connected to the storage spool 18 (Fig. 1) is a ratchet wheel 38 engageable by a driving pawl 39 pivoted at 41 (Fig. 2) to one of the side plates 4 of the printing frame. Also positioned to engage the ratchet wheel 38 is a locking or blocking dog or pawl 40 pivoted at 43 to one arm of the bell crank 22. Both pawls are urged in a clockwise direction into engagement with the ratchet wheel 38 by a spring 44 tensioned between the lower ends of the two pawls.

As the storage spool 18 is rocked bodily in a

counterclockwise direction to its Fig. 1 position, the ratchet wheel 38 moves with it, whereupon the driving pawl 39 engages one of the teeth of said wheel and causes the storage spool 18 to be rotated clockwise a predetermined distance, the driving pawl slipping off the ratchet wheel after the required rotation. The safety or blocking pawl 40 slides over the ratchet wheel during this operation and acts to prevent reverse rotation of the ratchet wheel 38 and storage spool 18.

The result is that, as the storage spool 18 is rocked downwardly in the operation of the mechanism for moving the paper from visible to printing position, the paper strip is advanced upward in the opposite direction the proper distance so that, when the paper strip is returned to visible position, the entry that has just been printed will be the one that is visible.

Further illustration and description of the record strip mechanism and of a cash register in which it is employed will be found in my aforementioned Patent No. 2,264,855.

Paper attachment and alignment

When the paper is slid back and forth from one position to the other, it must slide in a straight line. If it tends to slew off to one side, the edge of the paper will become torn and the mechanism will not operate properly. This requires that, when the paper strip is attached to the storage spool, it be properly aligned so that it will wind on said spool in a straight, uniform manner. Novel means has been provided for enabling the paper to be attached to the storage spool in such a manner that it will automatically align itself, and this means is a very simple one that can be quite easily used by the operator without any tedious adjustment to secure proper alignment of the paper.

Referring to Fig. 2, the storage spool includes a hollow sleeve 60 which is provided with a slot 61 through which the leading or free edge of the paper strip is inserted by the operator when starting a new roll of paper on the storage spool. The edges of the slot are separated an appreciable distance near the outer ends of the slot. These edges are brought close together near the longitudinal center of the slot. In the embodiment illustrated, this is obtained by having the trailing edge of the slot diverge from the center 62 toward the two ends of the slot, as will appear clearly from Fig. 2.

With this construction, the operator can very easily insert the paper by slipping it into one of the wider ends of the slot and moving it along the slot until it is approximately centered, after which he can turn the storage spool to start the paper winding about the hub. As he does this, the supply spool will offer a resistance to the movement of the paper and the effect is similar to that of a crown pulley, namely, that the paper automatically aligns and centers itself so as to wind evenly on the storage spool. The inner edge

of the straight end of the member 60 at the forward side of the slot keeps the end portion of the paper strip bent inwardly over the outer edge of the humped end of the member 60 at the rear side of the slot so that the paper strip may pivot considerably on the outer corner of the hump. The construction is very simple and inexpensive, yet automatic in its operation. The end of the paper strip does not have to be cut in any special way but is simply inserted in the slot. This aligning means has been found to be a very desirable feature in paper equipment of the kind described.

I claim:

15. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge having a centrally located hump extending circumferentially of said hub, said hub having means thereon for maintaining said strip so sharply bent around said hump as to prevent said strip from slipping during initial winding of said strip.
20. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge having a centrally located hump extending circumferentially of said hub, said hub having means thereon for maintaining said strip so sharply bent around said hump as to prevent said strip from slipping during initial winding of said strip.
25. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge having a centrally located hump extending circumferentially of said hub, said hub providing a second edge on the other side of said slot, the central portion of said second edge being positioned sufficiently close to said hump to maintain the received strip so sharply bent around said hump as to hold the end of said strip from slipping during initial winding of the strip.
30. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge having a centrally located hump extending circumferentially of said hub, said hub providing a second edge on the other side of said slot, the central portion of said second edge being positioned sufficiently close to said hump to maintain the received strip so sharply bent around said hump as to hold the end of said strip from slipping during initial winding of the strip.
35. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of said strip.
40. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of the strip.
45. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of the strip.
50. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of the strip.
55. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of the strip.
60. In a machine of the class described having means carrying a supply of paper strip, a rotatable spool on which said strip is wound, said spool having a hub provided with a slot therein for receiving the end of said strip and providing an edge on one side of said slot over which the strip received in the slot is bent upon winding of said strip, said edge diverging away from a line parallel to the axis of said hub on both sides of a central portion of said edge to provide a blunt apex located centrally of said edge and extending circumferentially of said hub, said hub providing a second edge on the other side of said slot extending substantially parallel with the axis of said hub, the central portion of said second edge being positioned sufficiently close to said apex to maintain the received strip so sharply bent around said apex to hold the end of said strip from slipping during initial winding of the strip.
